UNITED STATES PATENT OFFICE.

SANFORD D. LELAND, OF WELLESLEY HILLS, MASSACHUSETTS, ASSIGNOR TO MANUFACTURING EQUIPMENT & ENGINEERING COMPANY, OF SOUTH FRAMINGHAM, MASSACHUSETTS, A CORPORATION OF MASSACHUSETTS.

SHELVING.

1,136,245.

Specification of Letters Patent. Patented Apr. 20, 1915.

Application filed November 5, 1912. Serial No. 729,623.

To all whom it may concern:

Be it known that I, SANFORD D. LELAND, a citizen of the United States, residing at Wellesley Hills, county of Middlesex, State 5 of Massachusetts, have invented an Improvement in Shelving, of which the following description, in connection with the accompanying drawing, is a specification, like characters on the drawing representing 10 like parts.

This invention relates to shelving and especially to sheet metal shelving.

The objects of the invention are to provide a shelving of this nature which can be 15 easily and inexpensively manufactured; which is rigid and capable of supporting heavy weights; which has such a construction that anyone of the shelves can be removed or adjusted to different heights without disturbing any other shelves; and which is made in sections that can be quickly set up 20 or taken down to make a shelf structure of any desired length; and otherwise to improve shelving all as will be more fully 25 hereinafter described and then pointed out in the appended claims.

Referring to the drawings wherein I have 30 illustrated the preferred embodiment of my invention, Figure 1 is a perspective view showing a shelf embodying my invention; Fig. 2 is a section through one of the partitions on the line $x-x$, Fig. 3; Fig. 3 is a section through one of the shelves on substantially the line $y-y$, Fig. 2; Fig. 4 is a 35 perspective view of the corner bracket; Fig. 5 is a sectional view through one of the uprights and a portion of the partition showing the manner in which the partition and uprights become locked together when the 40 apertures are punched; Fig. 6 is a perspective view of the corner bracket showing the opposite side from that shown in Fig. 4.

My improved shelving comprises uprights, 45 partitions and shelves supported by the uprights. The uprights are designated by 1, the partitions by 2 and the shelves by 3. The uprights herein shown are made from sheet metal strips which are folded longitudinally to have a general U-shape and to 50 present the two sides 4 between which the edges of the partitions 2 are received, there being two uprights at each end of each shelf. I will preferably also fold the edges of the

uprights inwardly between the sides 4 thereby to present an inner wall 5 which is 55 substantially co-extensive with the outer wall 4.

The edge of the partition 2 is received between the inwardly-folded portions 5. The uprights are provided with a plurality of 60 apertures 6 to receive the bolts 7 on which the shelves 3 are supported. These apertures 6 are punched through the upright and the edge of the partition 2 after said edge of the partition has been inserted be- 65 tween the portions 5 of the upright, and in performing the punching operation the punch will form a slight bur 8 which will enter the hole formed in the partition 2, and this bur constitutes a means for locking the 70 upright to the partition so that after the holes 6 have been punched in the two uprights at both edges of the partitions said uprights and partitions become practically a unitary structure. 75

The shelves 3 are formed of sheet metal, and in order to stiffen the shelves I propose to bend the edges of them to form the downwardly-directed flanges 9. The lower edges of the flanges are also shown as bent in- 80 wardly, as at 10, and then upwardly, as at 11, this construction making the shelves very rigid. Each shelf has associated therewith at each corner a corner bracket designated generally by 12. Each bracket is formed 85 with the horizontal body portion 13 which underlies the shelf and which is permanently secured thereto by rivets 14, or in any other suitable way, and also with the vertically-extending flange 15 which is pro- 90 vided with the open-ended slot 16 and is adapted to engage the uprights 1. I also preferably make each corner bracket with a vertical flange 17 on the other side thereof, which stands at right angles to the flange 15, 95 said flange 17 lying against the vertical flange 9 on the shelf and being embraced by the portions 10 and 11 of the shelf, as clearly seen in Fig. 3. This flange 17 will also be riveted or otherwise secured to the flange 9 100 of the shelf. The corner bracket is permanently secured to the shelf.

The shelves are sustained in place by the bolts 7 which are inserted through the apertures 6 and the slots 16. The bolts are 105 each provided with nuts 18 which engage

the inner faces of the flanges 15 so that when the nuts are tightened the corner brackets are firmly clamped to the uprights. The shelves thus tie the uprights together and 5 make a rigid structure.

In setting up the shelving two partitions with their associated uprights are first placed the proper distance apart and the bolts 7 are inserted through the apertures 6

- 10 at the points where it is desired to locate the shelves. The shelves with their corner brackets may then be dropped into place, the slots 16 passing down over the bolts 7. When the shelves are properly located, the 15 nuts 18 are tightened to make the structure rigid. Each shelf is thus sustained by four bolts 7, but the shelves are independent from each other and any one shelf can be readily removed by simply loosening the nuts and 20 its supporting bolts and then lifting the shelf vertically to carry the slots 16 free from the bolts 7. This operation of removing the shelf does not in any way interfere with any of the other shelves, nor require 25 any loosening of the bolts supporting the said shelves or re-adjustment of them. The open-ended slots 16 permit this individual removal of the shelves, as will be readily understood.

- 30 The shelf structure may be made of any desired length by adding other sections each comprising a tier of shelves and where the entire shelf structure is the length of several shelves the ends of aligned shelves in adjacent tiers are sustained by the same bolt 7, as shown in Fig. 2. The construction is such, however, that the shelves in one tier can be readily arranged at different heights from the shelves of the adjacent tier.

- 35 40 The upright construction herein shown has the advantage that it is stiff and rigid and capable of sustaining a great weight without, however, being bulky, and has the further advantage that it can be very easily 45 formed from a strip of sheet metal.

While I have illustrated herein the preferred embodiment of my invention, I do not wish to be limited to the constructional features shown.

- 50 Having fully described my invention,

what I claim as new and desire to secure by Letters Patent is:—

1. In shelving, the combination with uprights, each formed with a plurality of apertures, of sheet metal shelves fitting between the uprights, each shelf having at each corner a corner bracket which is formed with a vertical flange to engage the upright and a horizontal flange or body underlying the shelf and permanently secured thereto, said vertical flange having an open-ended slot therein, and bolts extending through the apertures in the uprights and through said slots and by which the shelves are supported, said slots permitting any shelf to be removed without disturbing any other shelf.

2. In shelving, the combination with corner uprights formed from sheet metal bent into U-shape in cross section with the edges folded inwardly between the sides of the U, of partitions having their edges inserted between the inwardly-folded edges of the uprights, sheet metal shelves fitting between said uprights, corner brackets permanently secured to each shelf and detachably secured directly to the uprights whereby the shelves constitute the means for tying the uprights together.

3. In shelving, the combination with corner uprights formed from sheet metal bent into U-shape in cross section with the edges folded inwardly between the sides of the U, of partitions having their edges inserted between the inwardly-folded edges of the uprights, and sheet metal shelves fitting between said uprights, each shelf having at each corner a corner bracket which is formed with a vertical flange to engage the upright and a horizontal flange underlying the shelf and permanently secured thereto, said vertical flange having an open-ended slot, and bolts extending through the uprights and slots and by which the shelves are supported.

In testimony whereof, I have signed my name to this specification, in the presence of 95 two subscribing witnesses.

SANFORD D. LELAND.
